SCRAPER ATTACHMENT FOR A PAINT BURNER OR THE LIKE

Richard P. Hill, San Diego, Calif.

Application January 11, 1954, Serial No. 28,451

Term of patent 3½ years

(Cl. D9—6)

To all whom it may concern:

Be it known that I, Richard P. Hill, a citizen of the United States, residing at San Diego, in the county of San Diego and State of California, have invented a new, original, and ornamental Design for a Scraper Attachment for a Paint Burner or the like, of which the following is a specification, reference being had to the accompanying drawing, forming a part thereof, and wherein:

Figure 1 is a perspective view of a scraper attachment for a paint burner or the like, showing my new design;

Figure 2 is a side elevational view thereof;

Figure 3 is an end elevational view taken from the right end of Figure 2; and

Figure 4 is a top plan view thereof.
The dotted line showing of a paint burner in Figure 2 is for illustrative purposes only.

I claim:

The ornamental design for a scraper attachment for a paint burner or the like, as shown and described.
